MEANS FOR PACKING INSULATION MATERIAL

Robert D. Pauley, Cloquet, Minn., assignor to
Wood Conversion Company, Cloquet, Minn., a
corporation of Delaware

Application April 20, 1942, Serial No. 439,678

3 Claims. (Cl. 20—101)

1

The present invention relates to the packing of insulation materials, such as fibers, by differential pneumatic pressures.

In the co-pending application of Heritage Serial No. 477,753, filed March 2, 1943, as a continuation-in-part of a generic application Serial No. 294,212, filed September 9, 1939, there is disclosed a process and devices for blowing fibers, flakes, members and other insulation-forming material which packs or entangles to form a self-sustaining structure, into a space to build up an insulating body. In said description reference is made to a space to be filled with such insulation, which space is exemplified by a box-like structure with bottom and sides. The said space is such as that defined by a domestic refrigerator cabinet lying on its back with the door-opening directed upwardly, and by a fixture fitted into the cabinet as a dummy food compartment. The fixture is a special form provided variously with screen openings to permit exhaust of air used as a vehicle to bring in the insulation material. In actual practice, the said space is filled to provide an integrated continuous thermal insulation packing by use of the said fixture. Then the fixture is withdrawn, leaving the said packing unsupported on the faces where the fixture theretofore defined the space. The true food compartment is then inserted where the fixture had been. This results in the packing being continuous in all the space between the walls of the cabinet and the walls of the food compartment.

In such practice, especially using feltable fiber, difficulties are experienced on the side faces having a large vertical area so packed against a fixture wall which is imperforate over substantially the interior part of said area. There is a tendency, frequently exerted, for such vertical portion of the structure, comparable to a box side wall, to bulge inwardly and occasionally fall into the opening to be filled by the food compartment. The poorer the felting qualities of the material used, the greater is the tendency to collapse.

It is the object of the present invention to provide for pneumatically packing feltable insulation material to form a relatively thin and high vertical body covering a large vertical area, which body is stable when unsupported on one face by reason of removal of a wall defining said space originally.

In other words, in the specific case described, it is an object of the invention to prevent side-wall bulging or collapse.

It is a specific object of the invention to provide a fixture presenting in use a vertical side wall

2

of large area, which wall is largely imperforate, and which has imperforate horizontally spaced panels separated by vertically elongated and relatively narrow screen areas.

5 Various other and ancillary objects and advantages of the invention will be apparent from the following description and explanation of the invention as it is set forth and explained by reference to the accompanying drawings, in which the invention is explained by reference to structures employed with wood fibers having excellent felting properties compared to flakes, or to mixtures, or other insulating material in particle form.

15 In the drawings:

Fig. 1 is a view representing the appearance of a filled cabinet made with the fixture of Fig. 3.

Fig. 2 is a cross section taken on line 5—5 of Fig. 1.

20 Fig. 3 is a view of a fixture embodying the present invention, with one side wall rectified to the plane of the bottom wall only for the purpose of illustration.

Fig. 1 represents the goal to be attained. Numeral 10 represents a portion of a cabinet of a refrigerator lying on its back, providing a box-like shell. Some cabinets have the illustrated flange 11 about the opening, and some do not. However, the difficulties to be remedied are met with in both types. Numeral 12 represents fiber packed into the cabinet shell in box-like form to provide an opening in size to receive the food compartment.

The reinforcing ribs indicated 31 in Fig. 1 are effected by the present invention. Consider that these are lacking and the structure at them is like the indicated surrounding structure of the felted fiber. So considered, the filled cabinet is a product which when freshly made has exhibited 35 defects. The central portion of the long sidewalls (corresponding to the vertical sides of the upright refrigerator) may bulge or collapse, and the bottom also may bulge upwardly in the position shown in 1, when formed as hereinafter described by the older methods.

40 Fig. 3 represents roughly the type of fixture which has been employed to produce those structures of the defective type described, which tend to or do collapse or bulge. It is a box-like fixture, or dummy food compartment, of dimensions to define the interior walls of the space to be filled with insulation 12 (Fig. 1). It has a base or floor section 40 and four side panels 41, 42, 43 and 44, the latter being shown for convenience in illustration as rectified to the plane of the floor 40.

The curved arrow 45 indicates that the wall 44 should be raised to form the box-end. A conduit 48 into the floor receives air and fiber to discharge the same around the edges of the floor panel 40 and upwardly to fill the space adjacent panels 41 to 44. The packing begins at the top, grows downwardly, then horizontally toward the opening 49 pipe 48 leading to the space to be filled, thus filling the entire space with an integrated form. This method has been effected by having the various screen areas 46 near the tops of the panels and at the corners in the said panels and base, to release the air, filter the fiber, and induce a felted formation. The principles of the method are explained in detail in said prior application.

As a result of the use of the aforesaid fixture of Fig. 3, without the indicated screen areas 44, large areas of the felt lack a structure and strength which will maintain themselves in a vertical position unsupported from the inside, where the vertical area is large and horizontally long in proportion to the thickness of the felted panel.

Assume a fixture of Fig. 3 minus the screen areas 47 to be in the shell 10 of Fig. 1, and the material blown in to fill the intervening space. Thus, the material will pack from the top-most filter areas 46 downwardly, around the corners at the bottom, and then toward the inlet conduit 48. This results in a horizontally laminated formation, produced under pressure. As a result, substantially all the elasticity of the formation is exerted vertically in the side walls, and horizontally at the bottom (back of cabinet). Upon removal of the fixture and its restraint, the elasticity causes bulges in the long sides and bottom. The bulge at the bottom causes little difficulty, because upon inserting the food compartment it goes back into place under desirable compression. However, at the side walls, there is frequent collapse.

With fibers, the tendency to expand by the elasticity is transient, and upon standing the elastic force is converted into felting energy by rearrangement of the fibers. Thus, a cabinet so filled with the so-modified fixture of Fig. 3 may be allowed to stand for a considerable period of time before removing the fixture, to minimize or avoid the tendency to bulge. However, in commercial operations of this sort, it is not practicable to allow for such a time interval. The fixture must be removed immediately to permit filling another cabinet.

The present invention aims to alter the formation of the felt structure to provide selected portions of the felt with a different structure having greater strength and different elastic forces than the rest, whereby the selected portions act as a reinforcement, or as a break in the forces producing bulging. This is illustrated in Fig. 1, wherein the integrated felt form 30 in cabinet 10, has one or more vertical ribs 31 of a stronger and a differently felted-structure than the adjacent portions. The difference is illustrated in Fig. 2, by the more heavily shaded portion 31 which is formed over a limited screen area 32 in a fixture wall having the horizontally spaced imperforate panel portions 33 and 34 separated by the narrow vertically elongated screen area 32.

Where the felt is formed by exhaust of the air-vehicle outwardly from the felt 30-31 (Fig. 2) through the screen area 32, any finer fibers tend to filter out in the region 31, giving it greater

density and strength to provide the desired reinforcement or strut-formation. But also the formation tends to grow laterally from the areas 31 (Fig. 1) as well as downwardly, whereby a less laminated and a more random formation begins at areas 31 and extends therefrom into the surrounding area. The areas other than 31 in Fig. 1, which lie over screens are indicated, only by stippling.

The design of the fixture varies with the particular design of the box to be packed. For the structure shown in Fig. 1 a suitable fixture is shown in Fig. 3. In Fig. 6 the box-like form or fixture has an outside area substantially duplicating the exterior areas of the food compartment for the box 10. The screen areas 47 include those introduced in the long side walls to overcome the undesired defects. These are termed vertical intermediate screen areas, in that they extend generally vertically, compared to those horizontal areas 46, and lie intermediate the ends of the containing panel.

The conduit 48 in the center of the floor 40 is connected to a pneumatic supply of suspended fiber. It has an end opening 49 coincident with a like opening in the bottom or floor 40. By suitable arrangement for creating a differential pressure, a movement of air and insulating particles is effected through conduit 49 into the space to be filled. Thus, when the fixture is in the box 10 and the conduit 48 is connected to an outlet of a fan, into the inlet of which, or into the outlet pipe of which, fiber is fed, a charge of dispersed fiber is carried first to the remote screens 46 shown at the top of the fixture of Fig. 3, where it is felted and packed at a density determined in part by air pressure. As it packs, the edge surface of the felt being formed advances toward the pipe outlet 49, but the advancing surface changes shape in accordance with the arrangement of the screen outlets. The vertical screen areas 47 are very soon covered, and the advancing surface may move in part horizontally as well as vertically, away from such areas. The result is that a different and more random formation of fiber occurs over and away from the screens 41. These areas are those described as 31 in Figs. 1 and 2. They give support and relief to the resulting unitary mat, which prevent vertical side-wall collapse and bulging.

The extent to which the areas 47 are supplied, the extent of the space between two of them, the extent of their length, and the extent of their area, are a subject not capable of being defined. The differential air pressure, the depth of the felt, the properties of the insulating particles, and the over-all design of the fixture are all factors which are effective to control the character of the formation. Experience has shown that results are best obtained by a liberal initial supply of screen areas 46 and 47 generally as indicated in a fixture such as that in Fig. 3. One or more of these areas may be in whole or in part blocked off by use of adhesive tape to adapt the fixture to particular conditions for producing desired degrees of uniformity in density over the entire area to be filled.

Although the invention has been specifically illustrated by reference to its embodiment in the fixture for and in the production of refrigerators, it is to be understood that the invention is not confined to this embodiment. Any vertically standing slab-like body of fiber which is to be unsupported on one face for a time, where-

by it may be subjected to forces or reactions tending to cause its collapse, may be formed by use of a facial-member having imperforate panels horizontally spaced, and separated by one or more vertically elongated fiber-retaining gas-venting areas.

Although the invention has been explained by reference to the structures actually employed with wood fibers, it is to be understood that the principles of the invention apply equally well to cases where the feltable material which is used is not all wood fiber, or is some other material or mixture. It is to be observed that the end-walls of the fiber-box-structure described, corresponding to the top and bottom positions of the food compartment, are sufficiently short compared to the lengths of the other faces, that the support from the corners is sufficient to prevent side-wall collapse. It is to be understood that where the feltable material employed has such packing qualities that these short-length walls also tend to collapse, a vertical elongated screen area comparable to screen 47 may be used in the corresponding walls of the fixture to correct the defect.

Such structures and uses of the invention are comprehended within the scope of the appended claims.

I claim:

1. A fixture for use in insulating refrigerator cabinets by a pneumatic process, comprising a box-like form in the shape of a dummy for a food compartment for said cabinet, said fixture having a box-like bottom and four side walls corresponding generally to the back and side walls of said food compartment, the total area of said fixture having perforate area and imperforate area, of which total area perforate area in the bottom provides inlet area for introducing moving gas containing suspended particles of insulating material, and of which total area at least one side wall has filtering area and filtering means covering said area in the form of a narrow elongated area extending in the direction from bottom to top of the fixture intermediate the ends of the containing wall of the fixture, said elongated filtering area being flanked by imperforate area.

2. A fixture for use in insulating refrigerator cabinets by a pneumatic process, comprising a box-like form in the shape of a dummy for a food compartment for said cabinet, said fixture having a box-like bottom of rectangular form and two relatively long side walls and two relatively short side walls corresponding generally to the back and side walls of said food compartment,

the total area of said fixture having perforate area and imperforate area, of which total area perforate area in the bottom provides inlet area for introducing moving gas containing suspended particles of insulating material, and of which total area the said two relatively long side walls each have filtering area and filtering means covering said area in the form of a narrow elongated area extending in the direction from bottom to top of the fixture intermediate the ends of the containing wall of the fixture, said elongated filtering area being flanked by imperforate area.

3. Apparatus for forming a thin upright body of felted fiber in a space between two opposed vertical walls for use as thermal insulation, which body resists collapse when one of said walls is removed, which comprises, means providing an imperforate horizontally elongated vertical wall, means providing a horizontally elongated vertical fiber-confining second wall opposed to and spaced from said imperforate wall, said second wall containing in an area intermediate its horizontal extremities and closer to the middle between said extremities than to said extremities one or more narrow elongated vertically extending filtering-means capable of retaining the said fiber and of passing gas, said second wall being substantially imperforate on both sides laterally of said filtering means, and other fiber-confining means to partition said space from the atmosphere except for one or more openings through which to introduce into said space moving gas having feltable fiber in suspension, whereby when said gaseous suspension is introduced into said confined space in quantity to pack said space with felted fiber, gas is released in part at least through said narrow elongated vertically extending filtering means to build up immediately in contact with said filtering means a different fiber-felt formation than is built up laterally adjacent thereto, which first-mentioned formation provides reinforcement of the resulting fiber-felt against collapse upon removal of said second wall containing said filtering means.
